C. F. O. SEIBERT.
SPAT OR LEGGING,
APPLICATION FILED JAN. 23, 1922.

1,416,421.

Patented May 16, 1922.

Inventor:
Chas F. O. Seibert.

By John C. Hegdon
Attorney.

UNITED STATES PATENT OFFICE.

CHARLES F. O. SEIBERT, OF ST. LOUIS, MISSOURI.

SPAT OR LEGGING.

1,416,421.

Specification of Letters Patent. Patented May 16, 1922.

Application filed January 23, 1922. Serial No. 531,230.

To all whom it may concern:

Be it known that I, CHARLES F. O. SEIBERT, a citizen of the United States, residing at St. Louis, in the State of Missouri, have 5 invented certain new and useful Improvements in Spats or Leggings, of which the following is a specification containing a full, clear, and exact description, reference being had to the accompanying drawing, forming 10 a part hereof.

My invention consists in the novel construction and arrangement of parts herein-after particularly described and distinctly claimed.

15 The object of my invention is to provide an improved shoe-covering or spat, combined with an integral legging or puttee, which will be especially adapted for use by ladies and children, but which may also be 20 used by men; and which article will be of low cost, simple and easily applied and removed, and which will present a stylish, well-fitting, and ornamental appearance upon the foot and leg of the wearer.

25 In the drawing,

Fig. 1 is a side-elevation of my invention, as it appears in use upon both feet and both limbs of a lady.

Fig. 2 is an inside plan-view of the device, 30 vice, opened out, to show the interior construction, and

Fig. 3 is a side-elevation of the device, partly closed or folded.

In the form of my invention that is herein 35 illustrated, the numeral 1 designates the usual form of an over-gaiter, spat or shoe-covering, having formed integral with the upper edge thereof a legging, puttee, or leg-extension 2.

40 These may be formed, as shown, of a series of separate pieces or sections, united at adjacent edges by suitable seams or stitching 3; or the over-gaiter and legging may be made by cutting or pressing same from a 45 single solid piece of material, and thereby eliminate the said seams or stitching, and at the same time give the article the proper shape to fit the foot and leg of the wearer thereof.

50 Said over-gaiter 1 is provided with the usual heel-opening 4 and holding-down or instep-strap 5.

The inner flap 6 of the combined article is adapted to be folded inwardly, as shown 55 in Figs. 2 and 3, over the instep and leg of the wearer, and the outer (or closing) flap

7 is to be folded against, and made to overlap the adjacent over-gaiter 1 and its leg-extension 2, when the article is in use.

A long strap 8, which may be secured at 60 one of its ends to the spat or over-gaiter portion of the said overlapping closing-flap 7, by means of stitching or other fastening-means 9, or which may be formed integral with said flap, forms an extension of the 65 latter, and (in use) it is passed therefrom downwardly and under the shank of the shoe, and thence upwardly over the instep of the foot, and is thence made to spirally engage around and upon the overlapped closed 70 portions of the said legging, puttee, or leg-extension 2, in separated convolutions, as shown more clearly in Fig. 1.

The free upper end of the said spiral-strap 8 is to be secured upon and to the exterior of 75 the adjacent leg-extension 2, by means of a common buckle or other fastening-means 10, so that said strap may be pulled tightly around the leg, and then fastened while tight, to not only assist in securing the leg 80 and foot sections of the article in position, but also to prevent wrinkling of said strap and consequent unsightly appearance of the article.

Of course, said buckle or fastening-means 85 10 should permit of ready adjustment of said strap 8, in tightening, loosening, or removing same; and I do not limit myself to a buckle for this purpose.

Internal fastening-means, such as the ball-part 11, and the socket-member 12 of common snaps, should also be placed at the upper portion of the overlapping leg-extension 2, to hold the parts while the said strap 8 is being wound around the leg and shoe 95 members.

Instead of making the said long strap 8 flat, as shown, it may be round, in the form of a cord or braid; which is more or less elastic, as is the strap when made of flat 100 material; and if desired, the said strap may be made of elastic material, in whole or for a portion of its length.

In case the fastening-means 10 for the free end of said strap 8 is in the form of a common buckle having a tongue, a series of holes may be made in said strap to receive said tongue, in adjusting said strap.

Common stiffening-means, such as whalebone, or stiffening sections of cloth or other material 14, may be used to stiffen the various parts; and in the present illustration the

said sections of material 14 are in the form of friction-cloth, secured in place by means of glue or paste.

Said sections of friction-cloth 14 not only 5 act as stiffening-means, but they also prevent slipping of the overlapped parts upon each other. The same function would be performed (so far as slipping is concerned) by placing additional snap-members 11 and 10 12 on the parts which might slip out of shape.

I claim:—

A combined spat and legging, consisting of integral over-gaiter and leg-sections having 15 overlapping closing-flaps, and a long continuation of one of the said closing-flaps; one end of said long continuation being fixed

to the outer closing-flap of the over-gaiter section, and constructed and arranged to be passed therefrom downwardly and under the 20 arch of the foot, and thence upwardly and across the instep, and then spirally wound around overlapping flaps and body of said leg-section, in separated convolutions; and fastening-means at the free (or upper) end 25 of said long continuation.

In testimony whereof, I have signed my name to this specification in presence of two subscribing witnesses.

CHARLES F. O. SEIBERT.
